UNITED STATES PATENT OFFICE.

JOHN E. WOODBURY, OF WORCESTER, MASSACHUSETTS.

SHEET-FEEDING DEVICE.

Application filed May 16, 1922. Serial No. 561,409.

To all whom it may concern:

Be it known that I, JOHN E. WOODBURY, a citizen of the United States, residing at Worcester, in the county of Worcester and 5 State of Massachusetts, have invented a new and useful Sheet-Feeding Device, of which the following is a specification.

This invention relates to a machine for taking sheets from a sheet-separating 10 mechanism and manipulating said sheet-separating mechanism and delivering the sheets into the position to be removed either automatically or, ordinarily, by hand.

The principal objects of the invention are 15 to provide an entirely automatic arrangement for this purpose which will leave each sheet with its forward end elevated so as to be readily grasped by the operator, or removed by automatic means, if desired, connected so that the sheet separating mechanism will periodically remove a sheet from 20 the bottom of a pile in the feed-box timed in proper relation to the sheet feeding parts; to provide means whereby any delay 25 in the removal of the sheet from the position just described will automatically prevent further operation of the sheet separating mechanism and the further feed of a sheet forward into delivering position; to 30 provide pneumatic means for controlling the parts which in itself is controlled by the position of a sheet in its location above described ready to be taken away; to provide means whereby when the sheet just ready to 35 be delivered is still held by a pneumatic nozzle which manipulates it, the movement of this nozzle will be prevented automatically, the movement of the sheet separating device will be stopped, and the operation 40 of the sheet supporting grid which carries the sheet forward will also be arrested; and these parts will be automatically restored to automatic condition by the detachment of the sheet from its holding 45 nozzle; to provide simple and accurate mechanism for accomplishing these objects, and to so relate these mechanisms to each other that the machine will be capable of 50 operation by inexperienced help without the danger of delivering two sheets into the same position at one time or of injuring the parts of the machine.

Further objects and advantages of the invention will appear hereinafter.

Reference is to be had to the accompanying drawings, in which—

Fig. 1 is a plan of a machine constructed in accordance with this invention;

Fig. 2 is a side view of the same;

Fig. 3 is an end view of the same; 60

Fig. 4 is a horizontal sectional view on the line 4—4 of Fig. 3;

Fig. 5 is a central longitudinal sectional view on the line 5—5 of Fig. 3, showing the parts in the same position as in that 65 figure and in Fig. 2;

Fig. 6 is a longitudinal sectional view on the line 6—6 of Fig. 3, showing the carriage cam and connected mechanism;

Fig. 7 is a side view of details of the 70 pneumatic control also shown in Fig. 2 and illustrating them in a different position;

Fig. 8 is a side view of the slide mechanism, showing it in the position assumed 75 when the sheets are delivered;

Fig. 9 is a sectional view on the line 9—9 of Fig. 2;

Fig. 10 is a side view similar to Fig. 2, but showing mainly the pneumatic connections; 80

Fig. 11 is a similar view of a part thereof, showing the parts in a different position;

Fig. 12 is an end view of the pneumatic;

Fig. 13 is a central sectional view of the 85 same on the line 13—13 of Fig. 12;

Fig. 14 is a central sectional view of one of the pneumatic valves;

Fig. 15 is a longitudinal central sectional view on the line 15—15 of Fig. 1, showing 90 the parts in position for delivering one sheet and just ready to receive another.

Fig. 16 is a similar view showing the position of the parts when the sheet is being guided out of the supply box; and 95

Fig. 17 is a similar view showing the sheet still further advanced into a position between the feed rolls.

The invention is shown as embodied in a machine mounted on a frame 10 which can be located adjacent to and, if desired, partly supported by the frame of a printing press to which the sheets are to be supplied. The machine also can conveniently receive its 100

power from that printing machine although it is not confined to either of these features. For the latter purpose I have shown the driving shaft 11 mounted on said frame as provided with a sprocket wheel 12 receiving power from the printing machine shaft or any other source of power through a sprocket chain. On this shaft at the other side of the machine is a sprocket wheel 13 on which I have shown a crank arm 14 connected by a link 15 with an arm 16 fixed to a shaft 17 at the upper part of the machine. On this shaft at the opposite sides are two arms 18 connected by horizontal links 19 with a feed box 20 which slides on a horizontal frame 21 supported by the frame 10. At one end this box is pivoted on two studs 9 carried by vertically adjustable brackets 8 on the frame. These brackets are connected by a pivot cross bar 7 through which said studs pass. This cross bar has an integral arm 6 that can be adjusted vertically by a screw 5 to swing the bar about the pivots and raise and lower the inner end of a plate 26 carried by it. At the rear the frame 21 has two sockets 4 which rest on the tops of two ends on the frame to permit it to be swung up about the forward pivots 9 for access to the parts underneath.

The feed box 20 is without a bottom but the frame 21 is provided with a skeleton bottom 22 for supporting sheets in the box. This feed box is provided with an adjustable back plate 23 connected with the back of the box by adjusting screws 24 to make its effective length equal to the length of the sheets which are to be used in it. It will be understood, therefore, that the reciprocation of this feed box will move the sheets contained thereon as the back plate 23 projects down through the bottom 22, having slots in its end for receiving the longitudinal plates of which said bottom is formed. At the front of the feed box it is provided with an opening 25 into which projects the plate 26 having its end narrowed down and projecting toward a central opening 22^a in the bottom 22.

On one of the links 19 there is adjustably located a cam 27 which, when the feed box moves back, engages an arm 28 fixed on a shaft 29 and presses it down. This arm turns the shaft 29 upwardly slightly and brings an arm 30 at the center of it up toward the bottom of the bottom sheet in the feed box. This arm 30 is provided at its extreme end with a nozzle 31 pivoted thereon and connected with a hose 32 and through a valve 33 with an exhausting pump or source of air under reduced pressure. The means for creating the suction I have not shown herein, as it does not constitute a part of this invention.

The pivoted nozzle 31 is connected by a link 34 below the pivot with an arm 35 on a

cross shaft 36 at the end of the machine. On this shaft is an arm 37 connected by a spring 38 with a stationary part of the machine to normally pull this arm forward and the nozzle down out of operative position. At the other end of the shaft 36 is an arm 40 fixed thereon, and on the link 19 on that side there is adjustably fixed a projection 41 which, when the link moves back, engages this arm 40 and swings the nozzle up into a position in which its upper end is substantially horizontal. On the movement of the feed box forward, the projection 41 leaves the arm 40 near the beginning of the stroke and allows the spring 38 to swing the nozzle to an inclined position. This brings the extreme end of the bottom sheet below the projecting plate 26 and then the cam 27 moves beyond the end of the arm 28 and the latter is then free to swing up on account of the action of the spring 38. This moves the nozzle down bodily and takes the end of the paper as a whole down under the plate 26 and inclines it so that it can be pulled off along the nozzle without meeting any resistance from the suction. The continued rotation of the main shaft carries the feed box forward to the end of the plate 26 and the nozzle is so located as to guide the upwardly projecting edge of the sheet on the surface of a pair of rubber covered feed rolls 43 on the top of which are located a pair of steel rollers 44. These rollers are held down yieldingly on the rubber rollers by a spring 45. The shaft 46 on which the rubber covered feed rolls are located is operated by a sprocket chain 47 passing over the wheel 13 and a sprocket wheel on that shaft. Just as soon as the paper touches these rolls, therefore, the paper is moved forward and out on the receiving table which consists of a series of stationary horizontal plates 48 fixed at their outer ends but held up yielding at their inner ends which project over the shaft 46. This table, therefore, receives the sheet from the feed box and it is fed along the table by the operation of the rolls ready for the subsequent operations which will now be described.

On the shaft 11 is fixed a grid cam 50 shown as of heart-shape formation, operating a roll 51 on a bell crank 52 pivoted on a cross shaft 53 and adapted to swing freely thereon. A spring 54 draws this bell crank over so as to keep the roll in contact with the cam. The bell crank at the top is connected by a link 55 with a slide 56 on which is a grid composed of a plurality of flat plates 57. These are located slightly above the table 48 so as to really support a sheet of paper deposited from the feeding rolls. The slide is provided with a guide 58 extending to the rear to assist in keeping the rear up in horizontal position, and the sides of the slide are supported on horizontal tracks 130

59 adjustably supported by the frame inside.

Fixed on the cross shaft 53 is a bell crank 60 having a roll 61 operating on a heart-shaped carriage cam 62 on the main shaft 11. A spring 60^a holds the roll 61 against the cam 62. This cam is set about ninety degrees from the cam 50. To the upper part of the bell crank is pivoted a link 64 pivoted 10 to an arm 65 on a cross shaft 66, which is provided with another arm 67 extending up from it, and connected by a link 68 with a slide 69 operating on a horizontal rod 70 at the side of the machine which serves as a 15 support and guide for it. This slide has a stud on which there is a metal roller 49 running on a horizontal track 71 on the top of the frame to support the slide in horizontal position and control the position of 20 an oscillatable shaft 72 which extends out from the slide in the same direction and projects over the grid. This shaft 72 is pivoted on the slide in a bearing 73 with which it is provided. The shaft 72 extends from the 25 bearing concentrically for a distance, but is bent so that when the arm is oscillated in the bearing the end will rise and fall. This end has on it a hollow head 74 provided with a goose-neck 75 extending from it and having a downwardly extending inlet opening. The head is provided with a tube 76 extending from it back over the slide but movable with the head and connected by a 30 flexible tube 77 with a T 123 below which is connected in turn with a pump or other means for exhausting the air. It will be seen that the suction through this tube will result in holding a sheet of paper against the nozzle whenever the nozzle on the goose-neck 35 comes down so that the open end of the nozzle is sealed by the sheet.

Fixed on the end of the oscillatable shaft 72 there is a stop arm 78 adapted to engage a pin 79 fixed on the slide 69 to prevent the 40 shaft 72 moving at any time down to a certain point and preventing the head lifting the paper too high. This is a positive stop.

On this pin 79 is a spring 131 connected with a stud on the arm 78 for yieldingly 45 moving the shaft over to its extreme position and holding the head up. Also extending from this stop-arm is a branch having a fibre end 111 adapted, during the motion of the slide, to come into contact with an adjustable stop 109 located on a horizontal rod 110 supported by the frame. This stop can be adjusted to any position along the machine to bring the nozzle down on the 50 paper at any desired point in the travel of the slide.

Connected with the T 123 is a small casing 55 which has a flexible diaphragm 81 over its surface held in place by a plate 82 which is fixed to the frame and constitutes a support 60 for this casing. With the pump working to

exhaust the air through this system of tubes in the ordinary way, the diaphragm will not be affected by it, because the nozzle 75 at the end of the system is open. However, as soon as that nozzle is closed by a sheet of paper 50 the suction will act to draw in the diaphragm. The diaphragm is connected by a link 83 with a plate 84 loosely pivoted on the shaft 66, and held by a spring 85 yieldingly in one extreme position. This plate 84 is 55 provided with a long projecting arm 86, the upper end of which obviously is capable of moving slightly and is moved by the collapse of the diaphragm.

On the main shaft 11 there is another sprocket wheel 27 which by a chain operates a sprocket wheel on a cam-shaft 88 provided with a cam 89. This cam operates a roll on an arm 90 fixed on a stop-shaft 91. It is to be noted that on this arm 90 there is a pin 92 and a stop 93 having a notch in its lower side at the end toward the pin. Between the pin and the end of this stop there is room enough for the arm 86 to be received so that when the diaphragm is in its normal position the arm 90 can work up and down with the cam and is not affected by the diaphragm, but when the diaphragm is collapsed this arm 86 is pulled inwardly to the 90 position shown in Fig. 7 the next time the cam moves around to the position to raise the arm 90. This then will lock the arm 90 in its raised position and the cam 89 thereafter will rotate idly. The normal position is shown in Fig. 2 where this arm does not affect the operation of the arm 90.

On this shaft 91 is fixed a stop arm 94 which is adapted, when the arm 90 is raised, to engage a pin 95 on the bell-crank 52 and stop that in its rearmost position; holding its roller off the cam 50 and holding the grid back in its rearmost position.

Also fixed on the stop shaft 9 is an arm 96 having a notch 97 for engaging over a pin 98 on the upper arm of the bell-crank 60 which is fixed on the cross shaft 53. This holds that bell-crank forward and that roller away from its cam in the same way. This prevents the operation of the slide and nozzle, holding them in their forward position.

The suction tube 77 is connected with the pump or other source of suction through a flexible tube 99 which is connected with a valve 100 having a tube 101 that extends 110 to the pump. This valve 100 is provided with a plunger 102 which when in its lowermost position closes the connection to the pump and opens it when raised. The valve is provided with a stem 103 adjustably connected with the end of the lever 104. This lever has a roll 105 operating on a cam 106 also on the shaft 88. It is shown as of substantially the same shape as the cam 89, but located on the shaft in position about ninety 115

degrees from it. It will be obvious that this cam will open the connection to the suction once during each revolution and keep it open about a third of the revolution according to 5 the design of the cam.

On the lever 104 is an arm 107 having a projection 108 extending out over the arm 90 and adapted to be raised by it and held up when this arm is raised either by this cam 10 or by the locking means above described as 15 shown in Fig. 7. This holds the valve 100 open.

On the main shaft 11 is a cam 112 adapted 15 to raise periodically a roller 113 on an arm 114 pivoted freely on the cross shaft 53. A spring 115 holds the roll down on the cam and the cam is designed so as to hold the roller up throughout most of the revolution and drop it at a certain point in the revolution 20 of the main shaft. This arm is connected by a link 116 with a lever 117 above pivoted on a stud on the frame. The opposite end of this lever is adjustably connected with a valve stem 118 for allowing a 25 valve 119 thereon to drop periodically in the valve casing 33. This valve controls the communication between a suction pump or other source of suction and the flexible tube 32 which is connected with the nozzle 31 and 30 allows communication of that nozzle with the source of suction for a short period once during each revolution. This valve 119 can be held closed by an arm 120 on the stop shaft 91. This arm has a notch 121 for engaging a pin 122 on the arm 114 and holding 35 the valve 119 down.

It will be understood that this machine can be used apart from any other machine by itself, but I prefer to use it in conjunction 40 with a printing machine as for example, a die press, and I have shown notches 124 on the frame at one end for holding it on a rod constituting a part of such die press and supporting that end of this machine.

45 The operation is as follows: Starting with the feed box in the position shown in Fig. 15, the projection 27 depresses the arm 28 and moves the nozzle 31 up to its highest position and also the stop 41 engages the arm 40, 50 swings the shaft 36 back, and thus rocks the nozzle over into a position in which its upper open end is horizontal. At this time the valve 119 is elevated by the spring 115 which draws the roller 113 down into the low part 55 of the cam 112. Therefore the suction is connected in such a way as to draw down the end of the bottom sheet below the projecting end of the plate 26.

Now with the parts in this position it will 60 understand that the main shaft is continuing to rotate, and the feed box is just starting forward. As it goes forward the projecting end of the bottom sheet moves under the nose of the plate 26, the projection 41 leaves the arm 40, and allows the shaft 26

to swing down and this lets the nozzle 31 over into inclined position.

While in that position the paper can slide along it without resistance, but now the arm 27 moves away from the arm 28 and allows 70 the nozzle to swing down bodily and this pulls the paper down at the end. Just then the cam 112 comes around to the high spot and lowers the valve 119, shutting off the suction. This leaves the parts in the position shown in Fig. 16. Now the feed box continues to move forward and the sheet is soon brought to the position shown in Fig. 17 between the rollers.

It will be understood that the nozzle 31 80 is left throughout most of the rest of the rotation of the shaft 11 disconnected from the suction and inoperative ready to be again connected in the manner just described, when the rotation is about completed. Now 85 as the shaft continues to rotate the cam 50 commences to lift its roller and thus move back the grid 57. Just before this starts back the cam 62 commences to raise its roller and the shaft 66 commences to swing. 90 This shaft starts the carriage 69 forward on its guide 70.

It is to be remarked at this time that the nozzle 75 at the beginning of the above described motion was located in its lowermost 95 position on account of the action of the stop 111 and that the valve 100 was at the same time opened by the cam 106. Therefore the suction is connected to this nozzle and the sheet in advance of the one that has just 100 been referred to is thus brought under the control of this nozzle.

Now as the carriage moves forward, feeding 105 a sheet out of the feed box on the table, the sheet in advance is carried over by the 110 nozzle. As it moves over, the grids are brought back by the action of the grid cam 50, and the forward end of this sheet is elevated by the nozzle, and held in elevated 115 position by it. This nozzle remains in elevated position for part of the revolution and the operator is able to grip the sheet, as its end is lifted off the table and grid, and draw it off whenever ready. When she 120 draws it off the open end of the nozzle 75 is exposed to the air. Now the air current which has been passing through the tube 77 has previously been holding the diaphragm 81 in its retracted position so that the stop lever 86 is over in the position shown in Fig. 7 holding the lever 90 up. The effect 125 of this is to keep the valve 100 open and also keep the stop shaft 91 over in its position to hold the rollers off of the several cams 50, 62, and 112 in what may be called the elevated position. Thus, until the operator takes the paper off, these three cams although rotating cannot act to allow the rollers to descend toward the center. Therefore the grid is held back, the slide is pre- 130

vented from operating, and the valve 33 is closed, even if the cams rotate far enough to allow the opposite actions to take place.

Now when the operator moves the sheet a current of air is let into the tube 77 and the vacuum destroyed. The diaphragm 81 is released and the stop arm 86 is then moved back by its spring 85 into the position shown in Fig. 2, allowing the lever 90 to fall back on the cam 89 if this cam is far enough around and whenever moved around to the proper position. This swings the stop shaft 91 up again, and all the three stops just mentioned are moved out of operative position so that as the main shaft rotates its cams will function again. All this has left the sheet of paper with which we started on the grid. Now the nozzle 75 moves back to its starting point and then the grids start forward. The nozzle 75 then acts to bring the delivered sheet out into position for the operator to take it away. It is to be noted that the grids move forward and the nozzle moves back rapidly, so that if any of these actions are delayed by failure of the operator to take off the sheet, the sheet being delivered from the feed box can be carried out into the next operating position if the sheet is taken off before the cams get beyond their position for acting. Otherwise the main shaft can rotate as many times as may be necessary without delivering any more sheets from the feed box.

In this way it will be seen that the device is not only automatic but its operation is controlled by the action of the operator in removing the product from it, and the failure to do so will not result in the clogging of the machine by the feeding of additional sheets which otherwise would be in the way.

By controlling the operation of delivering the sheets from the feed box pneumatically and controlling the initiation of pneumatic movement by the position of the sheet itself, the device is made adaptable for practical operation in the art of printing letter heads and similar products. The operator who runs the die press is accustomed to take up sheets from the pile one at a time and this feeding device permits her to do that and yet provides the sheet always in the proper position for her to get a good hold of it by placing the thumb under its elevated end and yet will not deliver an additional sheet in that position if for any reason her attention has to be directed to the press or if she fails to take a sheet from the feeder in time for the next one to be set in position.

Although I have illustrated and described a single form of the invention and described it as applied to the feeding of sheets in a position for an operator to apply them to a die press, I am aware of the fact that modifications can be made in the construction and combinations of parts, and that it can

be used for feeding purposes of a different nature without departing from the scope of the invention as expressed in the claims. Therefore I do not wish to be limited to all the details of construction and combinations of parts or to the feeding for any particular machine, but what I do claim is:—

1. In a sheet feeding device, the combination with a reciprocating feed box, for reciprocating it, and means for separating the bottom sheet therefrom, of means for engaging the projecting edge of the bottom sheet and feeding it along as the feed box moves forward, pneumatic means for taking the sheet therefrom and elevating its end in position to be conveniently grasped by the operator, and pneumatic means for preventing the feeding of another sheet by the feed box until the previously fed sheet has been removed from the elevating means.

2. In a sheet feeding device, the combination with a reciprocating feed box and means for separating the bottom sheet therefrom, of pneumatic means for moving the sheet along and elevating its end in position to be conveniently grasped by the operator, and pneumatic means for controlling the operation of the feed box to prevent its feeding another sheet until the previously fed sheet has been removed from said elevating means.

3. In a sheet feeding device, the combination with a reciprocating feed box and pneumatic means for separating the bottom sheet from a pile of sheets therein, of means for engaging the projecting edge of the bottom sheet and feeding it along as the feed box moves forward, pneumatic means for taking the sheet therefrom and elevating its end in position to be conveniently grasped by the operator, and pneumatic means for controlling the operation of the feed box to prevent its feeding another sheet until the previously fed sheet has been removed from said elevating means and for preventing the first named pneumatic means operating at that time.

4. In a sheet feeding device, the combination with a reciprocating feed box and pneumatic means for separating the bottom sheet therefrom, of means for engaging the projecting edge of the bottom sheet and feeding it along as the feed box moves forward, pneumatic means for taking the sheet therefrom and elevating its end in position to be conveniently grasped by the operator, and pneumatic means for preventing the movement of the first named pneumatic means into operative position at that time and keeping it disconnected from a source of suction.

5. In a sheet feeding device, the combination with a pneumatic means for separating the bottom sheet from a pile of sheets, of means for engaging the projecting edge of the bottom sheet and feeding it along, pneu-

matic means for taking the sheet therefrom and elevating its end in position to be conveniently grasped by the operator, and pneumatic means for preventing the first 5 named pneumatic means operating at that time.

6. In a sheet feeding device, the combination with means for separating the bottom sheet from a pile and a set of feed rolls for 10 receiving the separated sheet and feeding it forward, of a movable carriage, a nozzle carried by said carriage for engaging the surface of the separated sheet, and means for moving the carriage forward and changing 15 the elevation of the nozzle.

7. In a sheet feeding device, the combination with means for separating the bottom sheet from a pile and a pair of rolls for 20 receiving the separated sheet and feeding it forward, of a reciprocable carriage, a nozzle carried by said carriage for engaging the end of the separated sheet, means for moving the carriage forward and raising the 25 nozzle to elevate the forward end of the sheet, and means for creating suction to hold the end of the sheet up with the nozzle.

8. In a sheet feeding device, the combination with means for separating the bottom sheet from a pile and a pair of rolls for 30 receiving the separated sheet and feeding it forward, of a reciprocable carriage, a nozzle carried by said carriage for engaging the end of the separated sheet, means for moving the carriage forward and raising the 35 nozzle to elevate the forward end of the sheet, means for creating suction to hold the end of the sheet up with the nozzle, and means whereby when the carriage is moved back the nozzle will be lowered.

40 9. In a sheet feeding machine, the combination with a table comprising a series of longitudinal bars located in fixed position, of a grid comprising a series of relatively fixed bars located between the bars of the 45 table and at a slightly higher level, means for moving the grid longitudinally to deliver a sheet, and a nozzle movable forward over the grid and adapted to engage the sheet to carry it forward.

50 10. In a sheet delivering device, the combination of a stationary table comprising a series of spaced bars fixed at one end and free at the other end, a carriage movable under said table and having a grid consisting of bars between said bars of the table 55 and located at a higher level and fixed to said carriage at their rear ends and free at their front ends, said table having means at the front for slidably supporting the free end of the grid, and means for moving said grid forward.

60 11. In a sheet feeding machine, the combination with a table, of a grid, means for moving the grid longitudinally to deliver a sheet, a nozzle movable forward over the

grid and adapted to engage the sheet to carry it forward, and means for moving the nozzle toward the table as it moves back to a position for receiving a sheet and for moving it away from the table as it moves toward delivering position. 70

12. In a sheet delivering device, the combination of a table for receiving the sheets, a carriage slideable along said table, a shaft oscillatably mounted on the carriage and 75 projecting over the table and having an eccentric end, whereby when the shaft turns said end will swing, a nozzle mounted on said end, and means for connecting said nozzle with means for creating suction there-through. 80

13. In a sheet delivering device, the combination of a table for receiving the sheets, a carriage slideable at the side of said table, a shaft oscillatably mounted on the carriage 85 and projecting over the table and having an eccentric end, whereby when the shaft turns said end will swing, a nozzle mounted on said end, means supported by the nozzle for connecting it with means for creating suction, means on the carriage for swinging the nozzle up normally, and means adjustably mounted for swinging the nozzle down when the carriage moves back to a position 90 to receive a new sheet. 95

14. In a sheet delivering device, the combination of a table for receiving the sheets, a carriage slideable along said table, an oscillatable shaft projecting over the table and having an eccentric end, whereby when the shaft turns said end will swing toward or 100 from the table, a nozzle mounted on said end, means for connecting said nozzle with a source of suction, and means for exhausting the air from said nozzle in all positions 105 of the carriage. 105

15. In a sheet delivering device, the combination of a table for receiving the sheets, a carriage slideable at the side of said table, a shaft oscillatably mounted on the carriage 110 and projecting over the table and having an eccentric end, whereby when the shaft turns said end will swing, a nozzle mounted on said end for engaging and holding a sheet, means on the carriage for swinging the nozzle up normally, means adjustably mounted for swinging the nozzle down when the carriage moves back to a position to receive a new sheet, a hose connection to the nozzle having a valve therein, and means for automatically permitting said valve to close 115 when the nozzle is moved to its extreme forward position. 120

16. In a sheet delivering device, the combination of a table for receiving the sheets, a carriage slideable at the side of said table, a nozzle swingingly mounted and projecting over the table for holding a sheet, means for connecting the nozzle with a source of suction, means for swinging the nozzle down 125 130

when the carriage moves back to a position to receive a new sheet, means for exhausting the air from said nozzle comprising a valve, means for automatically permitting said 5 valve to close when the nozzle is moved to its extreme forward position, and means for preventing the closing of the valve as long as the nozzle is closed by a sheet of paper.

17. In a pneumatic sheet feeding device, 10 the combination of a reciprocable nozzle capable of moving up and down, means for moving the nozzle upward as it moves along on its forward stroke to elevate a sheet with which it is connected, means for exhausting air from said nozzle, said means having a valve therein, and means for normally holding said valve open.

18. In a pneumatic sheet feeding device, 15 the combination of a reciprocable nozzle capable of moving up and down, means for moving the nozzle upward as it moves along on its forward stroke to elevate a sheet with which it is connected, means for exhausting air from said nozzle, said means having a 20 valve therein, means for normally holding said valve open comprising a cam, said cam being arranged to move out of operative position when the nozzle moves to the end of its stroke, whereby the valve can close, 25 and additional means for holding the valve open as long as the nozzle is closed by a sheet of paper.

19. In a sheet feeding device, the combination with a movable nozzle adapted to 30 engage a sheet of paper to feed it forward, pneumatic means connected with the nozzle for holding the sheet in contact with it until removed by hand, a lever having means for disconnecting said pneumatic means, means 35 for stopping the feed, a lever, controlling the feed stopping means, and a pneumatic device connected with said pneumatic means for preventing the operation of said lever to set the stopping device.

40 20. In a sheet feeding device, the combination of a reciprocable carriage, a nozzle carried thereby, means connected with the nozzle for normally creating a suction therethrough, whereby the nozzle is capable 45 of carrying a sheet along with it, a casing connected with said pneumatic means, an arm connected with said casing adapted to be moved into operative position thereby when the nozzle is closed by a sheet of 50 paper, a lever movable by the machine, means connected with said lever for operating the carriage, and means connected with said casing for preventing the operation of 55 said lever whenever the nozzle is in delivering position with a sheet covering it and adapted to be released by the uncovering of 60 said nozzle.

65 21. In a sheet feeding device, the combination of a reciprocable nozzle for engagement with the surface of a sheet, a

conduit connecting the nozzle with a source of suction, a valve in said conduit for closing and opening it, means timed to operate with the reciprocation of the nozzle for periodically opening said valve, and means 70 whereby when the nozzle is closed by a sheet of paper, the valve can not be closed until the sheet of paper is removed from the nozzle.

75 22. In a sheet feeding device, the combination of a reciprocating nozzle for engaging and moving a sheet, a conduit connecting said nozzle with a source of suction, a pneumatic diaphragm connected with said conduit to be held in one position thereby when the nozzle is closed by a sheet of paper, a stop arm pivotally mounted and connected with said diaphragm to control the connection of the conduit with said source of suction, a spring for pulling said stop arm over into inoperative position when the nozzle is open and the diaphragm is not under suction, and means controlled by said stop arm for operating the nozzle back and forth and for moving it up and down.

80 23. In a sheet feeding device, the combination of a reciprocable carriage, a nozzle on said carriage for engaging and carrying sheets, means for connecting the nozzle with a source of suction comprising a tube, a pneumatic diaphragm connected with said tube, a pivoted stop lever connected with said diaphragm, whereby the diaphragm will move it into operative position when under suction, a spring for 85 normally moving the stop lever into inoperative position, a cam, a lever operated by said cam and having a stop piece thereon under which the stop lever engages when pulled back by the diaphragm, a shaft on 90 which said lever is mounted, and means controlled by said shaft whereby when the lever is held up by the stop lever, the carriage is prevented from reciprocating and the connection of the nozzle with its source of suction is maintained.

95 100 24. In a sheet feeding device, the combination of a reciprocable carriage, a nozzle mounted on said carriage for engaging and carrying sheets, means for connecting the nozzle with a source of suction comprising a tube, a pneumatic diaphragm connected with said tube, a pivoted stop lever connected with said diaphragm whereby the diaphragm will move it into operative position when under suction, a spring for 105 normally moving the stop lever into inoperative position, a cam, a lever operated by said cam and having a stop piece thereon under which the stop lever engages when pulled back by the diaphragm to hold the lever off the cam, a shaft on which said lever is mounted, means whereby when the lever is held up by the stop lever, the carriage is prevented from reciprocating, a 110 115 120 125 130

valve connected with the tube for controlling its connection with a source of air under reduced pressure, an arm for holding the valve open, and means for engaging said arm and raising the valve to open it when the lever is held up by the stop lever.

25. In a sheet feeding device, the combination of a reciprocatable feed box, a nozzle pivoted to move up and down bodily and 10 also pivoted to swing on another axis into and out of the horizontal position for engaging a sheet at the bottom of a pile, a shaft having an arm on it for controlling the up and down motion of the nozzle, 15 means on said box for swinging said shaft when the box moves back to a certain position, a second shaft having means for controlling the swinging of the nozzle into horizontal position, and means movable with 20 the box for operating the second shaft.

26. In a sheet feeding device, the combination with a reciprocating feed box and means for separating the bottom sheet therefrom, of means for moving the sheet 25 along and elevating its end in position to be conveniently grasped by the operator, and means for controlling the operation of the feed box to prevent its feeding another sheet until the previously fed sheet has 30 been removed from said elevating means.

27. In a sheet feeding device, the combination with a reciprocating feed box and means for separating the bottom sheet from 35 a pile of sheets therein, of means for engaging the projecting edge of the bottom sheet and feeding it along as the feed box moves forward, means for taking the sheet therefrom and elevating its end in posi-

tion to be conveniently grasped by the operator, and means for controlling the operation of the feed box to prevent its feeding another sheet until the previously fed sheet has been removed from said elevating means and for preventing the first 40 named means operating at that time.

28. In a sheet feeding device, the combination with a means for separating the bottom sheet from a pile of sheets, of means for engaging the projecting edge of the bottom sheet and feeding it along, means for taking the sheet therefrom and elevating its end in position to be conveniently grasped by the operator, and means for preventing the first named means operating at 45 that time.

29. In a feeding device for a die-press attachment, the combination of a nozzle operated by vacuum to hold the sheet ready for the grasp of the operator, and sheet separating and nozzle operating elements 50 so arranged that when the sheet is not removed from the nozzle the functions of separating and moving into place of the subsequent sheets are suspended.

30. In a sheet-handling mechanism, means 55 for holding one sheet ready for the operator to grasp, while the sheet following occupies a space provided for it, and means connected with the first-named means for either separating or failing to separate the 70 third sheet in succession depending on whether the first sheet is or is not removed by the operator.

In testimony whereof I have hereunto affixed my signature.

JOHN E. WOODBURY.
